UNITED STATES PATENT OFFICE.

LORIN I. NEWTON, OF FORT DODGE, IOWA.

FURNACE-DOOR-OPERATING DEVICE.

SPECIFICATION forming part of Letters Patent No. 740,987, dated October 6, 1903.

Application filed October 25, 1902. Serial No. 128,751. (No model.)

To all whom it may concern:

Be it known that I, LORIN I. NEWTON, residing at Fort Dodge, in the county of Webster and State of Iowa, have invented certain new and useful Improvements in Furnace-Door-Operating Devices, of which the following is a specification.

My invention relates to furnace-door-operating devices; and it consists in improved means specially designed for operating locomotive fire-box doors, though adapted to be used in connection with any ordinary furnace, whereby the fireman may open and close the door with his foot, and thus leave his hands free for feeding fuel into the furnace, and thereby facilitate the coaling process in addition to opening and closing the door at each operation.

It is well known that firemen in general when it becomes necessary to shovel coal into the furnace leave the door open until that feeding is completed, and the reason therefor is that both of his hands are necessary to proper or advantageous handling of the shovel. Obviously when a furnace-door is kept open such length of time as from beginning to finish of the feeding process an unnecessary amount of cold air will rush into the fire-box and boiler-flues, causing them to cool off with such injurious effect as will or is likely to make them leak through repeated accompanying contraction of the parts.

To overcome the above objections, I have invented the hereinafter-described improved means whereby a fireman may open and close the fire-box door with one foot, leaving his hands free for advantageous handling of the shovel. It is obvious that when a furnace-door is left open during the feeding process the fire-box and also the flues will be cooled down, rendering a corresponding amount of additional coal necessary to reheat them, and to obviate which objection my invention is chiefly designed.

In order to enable others to make and use my invention, I will now proceed to describe it in detail with reference to the accompanying drawings, which form a part of this specification, and in which—

Figure 1 is a perspective view showing my invention in use. Fig. 2 is a view showing

my door-operating devices in modified form; and Fig. 3 is an inverted plan view of the furnace-floor, showing operating devices employed in the modified form of the invention. 55

It will be seen that in the embodiment of my invention I employ devices of peculiar construction and arrangement whereby a fireman may open and close a furnace fire-box door by simple pressure of one foot against a device located in the floor.

In carrying out my invention I employ an elongated rod 1, to which the door is fixed, and suitably support the same by brackets 2, in which latter the rod 1 rotates as the furnace-door is opened and closed. The upper end of the rod 1 is bent, forming an angular member 3, engaging with an upright extension 4, which latter with the member 3 provides the upper end of the rod 1 with a crank-shaped upper end, from which extends a spring 5, having its other end secured to the front of the furnace, substantially as shown, and operating to hold the door yieldingly closed. 75

6 indicates an arm projecting out from the front of the furnace and providing at its outer end pivotal support for a lever 7, whose outer or longer end 8 is connected by a rod 9 with the end 4 of the crank-shaped upper end of 80 the rod 1. From the shorter end 10 of the lever 7 extends a rod 11, connecting the crank 12 at the upper end of a revoluble rod 13. This rod extends down through the furnace-hearth or a locomotive-cab floor and is bent 85 at an angle, as at 14, and then extended upwardly at 15, with the end of the latter projected through a curved or other suitably-shaped guideway-opening. When pressure is exerted against the upper end or foot-piece 90 17 of the member 15, the guideway 16 will allow horizontal or sidewise movement of the foot-piece and impart turning action to the rod 13, and thereby movement of the crank 12.

With the parts constructed and connected 95 as above described and shown by my drawings it is apparent that a fireman has simply to press his left foot against the foot-piece 17, projecting up through the floor, when a partial turn will be imparted to the rod 13, and thereby through the crank 12, rod 11, lever 7, rod 9, and crank-shaped upper end of the

rod 1 swing open the furnace-door against tension of the spring 5. Now when pressure is removed from the foot-piece 17 it is apparent that the spring 5, it being under tension, 5 will operate the cranked upper end of the rod 1 with effect to close the furnace-door and also return all the parts through their connections to first or normal position.

As above described, all the working parts 10 save the member 14 are located above the hearth or cab-floor; but the same may be located under the hearth or cab-floor with slight modification or change, as I will now proceed to describe. In its modified form the 15 rod 1, supporting the furnace-door, is extended down through the hearth or cab-floor and is provided at its lower end with a crank 18, displacing the similar crank members 3 4, above described. The arrangements of 20 parts under the floor are substantially the same as in the arrangement thereof first described, but dispense with the revoluble rod 13 and its crank member 12. In the modified arrangement an arm 19 is used, having 25 one end pivoted to a bracket 20 and its other end connected with a rod or link 21, extending from one end of a lever 22, pivoted at 23 to a bracket 24. The opposite end of the lever 22 connects the crank 18 on the lower end 30 of the door-supporting rod 1 by a link or rod 24. With the construction and arrangement of parts last described the operating foot-piece 17, substantially as first described, projects up through a slot 25 in the floor and is 35 connected with the lever 12 at 26, as shown.

27 indicates a spring having one end fixed and the other end secured to the crank 18. This spring operates to yieldingly hold the furnace-door closed and serves substantially 40 the same as the spring 5, hereinbefore referred to, and used with the arrangement of parts above the floor.

The joints of all rods and cranks and also the furnace-door hinges may be made adjustable, as indicated by 28 in all the views.

Having thus fully described my invention,

what I claim as new, and desire to secure by Letters Patent, is—

1. In combination with a furnace-door held yieldingly closed and adapted to be opened 50 through mechanism extending from an operating-piece in front of the furnace, a vertical rod fixed to and forming one hinge member of the door, a crank member at one end of said vertical rod, a spring having one end 55 fixed and its other connected with the said crank and adapted to hold the door yieldingly closed, an elongated angularly-arranged guide-slot in the furnace-hearth or floor, a foot-piece projecting up through the said 60 guide-slot having horizontal or sidewise movement as specified, and connecting means between the said foot-piece and the crank at one end of the said vertical rod or hinge member, substantially as described. 65

2. The combination with a furnace-door, of a vertical rod fixed to the door and forming one hinge member, a crank at the upper end of said vertical rod, a fixed spring connecting the said crank at the upper end of the vertical rod or hinge member and operating to hold the door yieldingly closed, a bracket projecting out from the front of the furnace, a lever having pivoted support at the outer end of the said bracket with a shorter and longer 70 end as specified, a rod extending from the longer end of the said pivoted lever to the crank at the upper end of the vertical rod or hinge member, a rod extending from the shorter end of the said pivoted lever to an 75 operating-crank, a revoluble rod having at its upper end an operating-crank and with its lower end extending below the hearth or cab-floor, a guideway-slot in the hearth or cab-floor, a foot-piece projecting up through the 80 said guideway-slot and having a crank-acting connection with the lower end of the said revoluble rod, substantially as described. 85
